DESIGN FOR A DISPLAY PLATE FOR AN AUTOMOBILE

Thomas Grimes, Santa Barbara, Calif.

Application January 15, 1941, Serial No. 98,091

Term of patent 3½ years

To all whom it may concern:

Be it known that I, Thomas Grimes, a subject of the King of Great Britain, residing at Santa Barbara, in the county of Santa Barbara and State of California, have invented a new, original, and ornamental Design for a Display Plate for an Automobile, of which the following is a specification, reference being had to the accompanying drawing, forming part thereof.

I claim:

The ornamental design for a display plate for an automobile, as shown.

THOMAS GRIMES.
